UNITED STATES PATENT OFFICE.

CHRIS MATTHEWS, OF SAN PEDRO, AND CHARLES S. HALL, OF LOS ANGELES,
CALIFORNIA.

AEROPLANE.

1,307,826.

Specification of Letters Patent. Patented June 24, 1919.

Application filed October 24, 1918. Serial No. 259,488.

To all whom it may concern:

Be it known that we, CHRIS MATTHEWS and CHARLES S. HALL, citizens of the United States, residing at San Pedro and Los Angeles, in the county of Los Angeles and State of California, have invented new and useful Improvements in Aeroplanes, of which the following is a specification.

Our invention relates to an improvement 10 for aeroplanes in the form of a lifting or stabilizing device.

An object of our invention is to provide an attachment for aeroplanes which will enable the machine to rise more directly from 15 the ground than is possible with aeroplanes as presently equipped.

Another object is to provide a stabilizer for an aeroplane in case one of its wings becomes broken.

20 Another object is to provide a retarding device by means of which the lighting of an aeroplane may be more easily and more safely effected.

With these and other objects in view our 25 invention consists in the construction, combination and arrangement of parts herein-after described and claimed.

In the accompanying drawings which form a part of this specification,

30 Figure 1 is a plan view of an aeroplane with its right wing broken away, showing the arrangement of our lifting device as seen from above.

Fig. 2 is a view in side elevation of the 35 machine shown in Fig. 1 with a part of the body shell broken away to show the connections between the lifting propeller and the engine, and also their position in the aeroplane.

40 Fig. 3 is a reduced view of the aeroplane shown in Fig. 2 illustrating the action of the propellers and the air currents produced by them.

Fig. 4 is a view in front elevation of the 45 aeroplane shown in Fig. 1, looking in the direction indicated by arrow 4 in Fig. 1.

Fig. 5 is an enlarged fragmentary sectional view on the line 5—5 of Figs. 1 and 4.

Fig. 6 is a still further enlarged sectional 50 view taken on the line 6—6 of Fig. 5 and showing the mechanism for tilting the planes endwise.

The aeroplane shown in the drawings represents a common form having a body 10, a propeller 11, wing planes 12 and 13 and the

usual guiding planes. An engine 14 is fixed to the forward part of the body shell and the propeller 11 mounted on the forward end of the shaft in the usual way. The engine shaft has an extension 15 on its rear end and 60 to this extension is connected, by a universal coupling 16, a rearwardly extending shaft 17. The rear end of the shaft 17 is journaled in a bracket 18 fixed to the floor of the body shell and has a miter gear 19 keyed 65 on its extreme rear end. A companion miter gear 20 is fixed to a vertical shaft 21 which has its lower end journaled in the bracket 18. The vertical shaft 21 extends upwardly through the top of the body shell and has 70 fixed to its upper end outside the shell, a propeller 22, the upper end of the vertical shaft 21 being journaled in a thrust bearing 23 fixed in the roof of the shell. The propeller 22 is so placed that it is above the 75 center of gravity of the aeroplane as a whole, and at the same time its shaft approximately coincides with the longitudinal balancing point of the machine, so that in flying the upward lift or pull is such as to hold the 80 aeroplane in an approximately horizontal position without any tendency to tip endwise.

Attached to the vertical struts 24 and 25 on each side of the aeroplane body by means 85 of arms 26, 27, 28 and 29 are two swivel members 30 and 31 which surround the aeroplane body and in which the aeroplane body is adapted to turn. Each of the swivel members consists of two vertical ring plates 32 90 and 33 held in parallel relation to each other by a series of spool shaped rollers 34 mounted between them on pivot pins 35 which extend through the rollers and ring plates.

The ends of the pivot pins are fixed in the 95 ring plates so as to hold them in fixed relation to each other, and the rollers are adapted to turn on the pivot pins in engagement with a beaded ring 36 fixed around the body of the aeroplane. A segment of the upper 100

part of the forward beaded ring is cut away to provide for an arcuate rack 37 which is fixed between the ring plates 32 and 33 and has its teeth 38 extending inwardly and meshing with a bevel gear 39 keyed to a 105 shaft 40. The inner ends of arms 26, 27, 28 and 29 are fixed to the ring plates 32 and 33 of the swivel members. One end of shaft 40 is journaled in a bracket 41 fixed in the roof of the body shell and the other end ex- 110

tends rearwardly and is journaled in an instrument board 42 extending across the body shell. A hand wheel 43 is fixed on the rear-most end of shaft 40 in a position easily accessible to the aeronaut when in the seat 44 of the aeroplane. A rack slot 45 is cut in the body shell to provide for the rack and its movements in relation to the body.

Operation: As readily may be seen the engine drives both propellers simultaneously and the front propeller operates to pull the machine forwardly while the top propeller at right angles to it operates to lift the machine straight upwardly. There are, therefore, two forces at right angles to each other, the resultant of which is a force acting between them along the line roughly indicated by arrow —a—. In other words, as shown in Fig. 3, the air currents produced by the vertical and horizontal propellers, interfere and take a direction indicated by arrow —b—, and the reaction of this resultant current lifts the machine in the direction indicated by arrow —a—.

In making a turn it is desirable to tilt the planes endwise while the body is maintained in its upright position because of the gyroscopic stabilizing action of the rapidly revolving horizontal propeller. In order to do this the hand wheel 43 is operated to turn shaft 41 and the bevel gear 39 which engages with the rack teeth 38. The ring plates 32 and 33 of the swivel members 30 and 31 are thus pulled around on the body shell, the rollers 34 of the swivel members traveling on the beaded ring 36. The planes 12 and 13 which are rigidly attached to the ring plates 32 and 33 by arms 26, 27, 28 and 29 move with the ring plates, so that their ends on one side of the body are raised while those on the other side are lowered.

It is evident that the combined effect of the two propellers is to lift the aeroplane much more directly upward than is possible with one propeller. The ascent can therefore be made much more quickly with the lifting propeller. It is evident also that in descending, though the speed of the propellers will necessarily be reduced, the lifting propeller will prevent the machine from falling as rapidly as it otherwise would, and consequently the descent can be made more easily and safely. The rapid rotation of the lifting propeller in a horizontal plane, also acts on the principle of a gyroscope to

stabilize the machine for which reason the mechanism for tilting the planes is a desirable, if not a necessary, provision for safety and convenient management of the machine in making turns.

60

While we have shown the preferred construction of our lifting propeller in its application to an aeroplane, it will be understood that various changes in construction and arrangement of parts may be made by those skilled in the art without departing from the spirit of our invention as claimed.

We claim:

1. The combination with an aeroplane, having a body equipped with an engine and wing planes of a lifting propeller comprising, an extension shaft adapted to be coupled to the aeroplane engine shaft, a vertical shaft adjacent said extension shaft, a bearing bracket in which said extension shaft and vertical shaft are journaled, a lifting propeller fixed to the upper end of said vertical shaft and a steering device comprising swivel members each of which include a groove ring provided with rollers which are fixed to the wing planes and a beaded ring fixed to the body of the aeroplane in co-operative relation with the grooved ring, an arcuate rack fixed in one of the grooved rings, a shaft adjacent said arcuate rack, a bevel gear fixed on the end of said shaft in operative relation with said rack, and a hand wheel fixed to the opposite end of said shaft, said lifting propeller operating to lift the aeroplane and said steering device being adapted to tilt the wing planes longitudinally in coöperation with said lifting propeller when making a turn.

2. In an aeroplane, an aeroplane body, swivel members connected to the aeroplane body, wing planes connected to the swivel members, each of said swivel members including a grooved ring provided with rollers fixed to the wing planes, a beaded ring fixed to the body in coöoperative relation with the grooved ring, an arcuate rack fixed in one of the grooved rings, a shaft adjacent said arcuate rack, a bevel gear fixed on the end of the shaft in operative relation with the rack, and a hand wheel fixed to the opposite end of the shaft.

In testimony whereof we have signed our names to this specification.

CHRIS MATTHEWS.
CHARLES S. HALL.
